US00D545126S

(12) **United States Design Patent** (10) **Patent No.:** **US D545,126 S**
White (45) **Date of Patent:** **** Jun. 26, 2007**

(54) **LID FOR BLENDING APPARATUS**(75) Inventor: **Martin White**, West Malling (GB)(73) Assignee: **McGill Technology Limited**, Kent (GB)(**) Term: **14 Years**(21) Appl. No.: **29/266,692**(22) Filed: **Sep. 27, 2006****Related U.S. Application Data**

(62) Division of application No. 29/238,982, filed on Sep. 26, 2005, now Pat. No. Des. 535,523.

(30) **Foreign Application Priority Data**

Sep. 9, 2005 (EP) 000399571

(51) **LOC (8) Cl.** ..... **07-02**(52) **U.S. Cl.** ..... **D7/412**(58) **Field of Classification Search** D2/869; D7/306, 309, 311, 376-386, 412, 413, 415, D7/509, 523, 529, 530; D15/5, 7, 126, 139, D15/148; D23/379, 411; 99/348, 509-511; 241/30, 33, 37.5, 101.01, 101.1-101.2, 282.2, 241/301, 285.1-285.2; 366/64, 65, 129, 366/197-214, 219, 241-254, 314, 341, 349; 415/121.1, 183, 188

See application file for complete search history.
